UNITED STATES PATENT OFFICE.

FERDINAND KERN, OF NEWARK, NEW JERSEY, ASSIGNOR OF THREE-FOURTHS TO HEILNER & STRAUSS, OF NEW YORK, N. Y.

BOBBIN-RETAINING DEVICE FOR SEWING-MACHINES.

SPECIFICATION forming part of Letters Patent No. 436,002, dated September 9, 1890.

Application filed November 9, 1889. Serial No. 329,728. (No model.)

To all whom it may concern:

Be it known that I, FERDINAND KERN, of Newark, New Jersey, have invented a new and useful Improvement in Sewing-Machines, of 5 which the following is a specification.

This invention consists in an improved mechanism by which the shuttle-bobbin is held in place in a sewing-machine of the rotary-shuttle class.

10 Figure 1 is a face view of the shuttle and the stationary head within which it revolves, the bobbin and bobbin-case being removed. Fig. 2 is a view of the same with the bobbin and bobbin-case in position. Fig. 3 is a side view of the same. Fig. 4 is a longitudinal section of the same. Fig. 5 is a plan view of the same. Fig. 6 is an isometric view of the bobbin-case detached.

15 *a* is the shaft, upon the end of which is mounted that portion of the stitch-forming mechanism which is below the table of the sewing-machine. This revolves within the stationary head *b* fixed beneath the table. This stitch-forming mechanism is held within 20 the stationary head *b* by means of a face-plate *c* screwed onto the face of the stationary head *b*.

25 In the space *d* within the shuttle, Fig. 1, centered by the hollow spindle *e*, which is fixed upon a shuttle and coincides with the center of rotation, is placed the bobbin *f*. This bobbin is inclosed within a bobbin-case *g*, which has a spindle *h* extending inversely to the spindle *e* and fitting within the same. By this construction the bobbin is enabled to turn with respect to both the shuttle and the bobbin-case, while the shuttle is enabled to turn as the bobbin-case remains stationary.

30 In order to provide for holding the bobbin-case in position to prevent its turning in operation, it is provided with an upwardly-projecting nose *i*, which overlaps the recess in the stationary head provided for the descent of the needle. Upon the exterior of this nose is located the tension-spring *k*. All of the 35 parts up to this point are old and well known, and a more detailed description of them is therefore unnecessary.

The novel part consists in the means by 40 which the case *g*, containing the bobbin is held

in position for operation, so as to be readily removable, when desired, in the direction of the arrow, Fig. 4, it being noticed that thus far in the description no device has been mentioned which would prevent the bobbin-case 55 from falling out of the shuttle. To prevent this and at the same time permit the easy removal of the bobbin-case, I provide the spring *l*, which is secured at one end to the face-plate *c* at one side, and extends horizontally across 60 outside of the nose *i* when the latter is in a vertical position. This spring *l* is so adjusted that when the parts are in position for sewing the portion *m*, which is directly outside of the nose *i*, does not press upon the same, 65 but provides sufficient clearance, as shown in Figs. 4 and 5. The clearance thus provided prevents the presence of the spring *l* from interfering with the proper operation of the other parts. To one side of the portion *m* the 70 spring *l* is provided with an indentation *n*, which extends inward toward the face-plate so far as to prevent the passage of the nose *i* behind it without raising the spring *l*. When the parts are in position for sewing, the nose 75 *i* rests against one end *o* of the face-plate, which extends far enough out toward the spring *l* to prevent the passage of the nose *i* between the two. Now it will be apparent that the nose *i* will be prevented from rotating with the stitching mechanism in one direction by the end *o* of the face-plate and in 80 the other direction by the indentation *n* of the spring *l*. It will likewise be held from falling out of the shuttle by the spring portion *m*. It still remains, however, to provide for the removal of the bobbin and bobbin-case *g*. This is done by cutting the spring *l* away at the point *p*, so that by raising the 85 spring and permitting the nose *i* to pass under the depression *n*, it will find at the cut-away portion *p* a free passage for it out of the shuttle in the direction of the arrow, Fig. 4. The cut-away portion *p* is sufficiently distant from the spindle *e* so that the spring *l* will not 90 overlap the nose at that point.

In practice it will not be necessary to actually raise the spring *l*, since the depression *n* forms an incline on both sides, which will cause the spring to raise when the nose is 95 100

pushed around in either direction against the indentation *n*. Thus to remove the bobbin the operator need merely press the bobbin-case around in the direction of the arrow, 5 Fig. 2, until the nose comes opposite the opening *p*, and then remove it. The bobbin will come away with it. After changing the bobbin the operator merely reverses this movement to insert it again. The end *o'* of 10 the face-plate lies so flat against the head *b* that the forward inclination of the nose causes the two to clear each other as the bobbin-case is removed.

I claim—

15 1. In a rotary-shuttle machine, in combination, the bobbin, the bobbin-case provided with a nose, a face-plate provided with an opening in which the nose projects, and the stationary spring overlapping said nose and 20 provided with a projection under which the

nose is obliged to pass in removing the bobbin-case, substantially as set forth.

2. In a rotary-shuttle machine, in combination, the shuttle, the bobbin, the bobbin-case provided with an upwardly-extending nose, 25 the face-plate provided with an opening to receive said nose and with an outward projection *o* at one side of said opening, whereby the bobbin-case is prevented from rotating in that direction, and a spring overlapping said 30 opening and provided on the opposite side thereof to the projection *o* with an inward projection, whereby the bobbin-case is arrested from operation in that direction, substantially as described.

FERDINAND KERN.
